DEVICE FOR KEEPING BAGS OPEN WHILE
BEING FILLED

Hermann Schultheiss, Basel, Switzerland

Application March 29, 1947, Serial No. 738,123
In Switzerland January 15, 1946Section 1, Public Law 690, August 8, 1946
Patent expires January 15, 1966

2 Claims. (Cl. 248—100)

1

The invention relates to a device for keeping bags open while they are being filled, with a frame with self-clamping holding-clamps for the bag, which frame is adaptable for various sizes of bag openings and besides adjustable in height on a column.

The device is new in that the frame which carries the self-clamping hook shaped clamps is open on one side, and is mounted on a carrier which can be shifted in a column and which can be locked in various positions of extension. The column itself is connected with the base plate in such a manner that it can be swiveled, and that it can be locked in the vertical position. Due to this arrangement the column can be laid flat on the base plate while the frame can be rotated into that central plane through the column, which is perpendicular to the plane in which the column moves. The whole arrangement is such that the device occupies a minimum of space when it is used.

Other objects and advantages will be in part obvious from the annexed drawing and in part hereinafter indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the modifications in structure and relation contemplated by this invention, a drawing depicting a certain form of the invention has been annexed as a part of this disclosure, and in such drawing, like characters of reference denote corresponding parts throughout all the views, of which:

Fig. 1 is a side view of the device.

Fig. 2 is a partial top view of the device.

Fig. 3 is a cross-sectional view taken along line III—III in Fig. 1.

Fig. 4 is a view of the holding device for the column, in direction of the arrow A in Fig. 1.

Fig. 5 is a view of the part of the device that carries the frame, viewed in direction of the arrow B of Fig. 2.

Fig. 6 is a cross-sectional view taken along line VI—VI of Fig. 2 on a larger scale.

Fig. 7 is a top view of the frame, according to a variation in a detail, on a smaller scale.

Fig. 8 is a cross-sectional view taken along line VIII—VIII in Fig. 7 on a larger scale.

Referring now more particularly to the draw- 55

ings, on a base plate 1 are arranged two guide plates 2 in shape of a sector of a circle. One end of a column 3 is connected with these plates by means of bolt 4. The end of this column is closed 5 with a plate 5 which in addition to functioning as end plate, functions also as a base plate on one end of which the bolt 4 is located. On column 3 there is a rib 6 which extends to plate 5; a holding member 8 is connected to this rib by means of a pin 7 and the free end of the holding member 8 carries a cross-bar 9 of circular cross-section. One end of each of the plates 2 has a notch 2a which serves as stop for the cross bar 9 of holding member 8. 10 Column 3 is hollow and has a square cross-section; a bar-shaped carrier 10, also with square cross-section is inserted in the column in such a way that it can be moved lengthwise. Clamping screw 11 serves to lock carrier 10 in any desired 15 position. The free end of carrier 10 is connected with a piece of tubing 10a whose axis is perpendicular to the longitudinal axis of the carrier 10. A U-shaped frame 12 is supported in this tubing 10a in such a way that it can be rotated; the 20 cross bar between the two arms of this frame has two stops 13 of such an arrangement and shape that the frame cannot be shifted axially but that it can be rotated by approximately 270° in the direction indicated in Fig. 1 by the arrow C. In 25 the position according to Fig. 1, however, the two plates 13 make contact with rib 14 on carrier 10. 30 Each of both arms of the frame for holding the bag carries a round bar 15, parallel to the arm; two holding clamps 16 are mounted on each 35 bar in such a way that they can be shifted lengthwise and also rotated. The holding clamp 16 (Fig. 6) has the shape of a hook with the axis of rotation at one end; the hook-shaped other end 16b is designed in such a way, that the bag can 40 be put on the frame without lifting each hook separately. Corner 16c prevents that the hook is opened too far, so that the hook always makes contact with the point 16a of the arm of the frame which has the shape of a round bar. Hook 45 16 grips a bag 17 which is put underneath and which exercises a pull downwards; by reacting on the hook the bag increases its clamping effect. The holding clamps 16 are, therefore, self-holding. If the device is not, in use, columns 3 can be 50 lowered on to the base plate 1 by rotating the holding member 8 in direction of the arrow D (Fig. 1) so that it (the member 8) leaves the notches of the two plates 2. This is done by rotating column 3 by 90° in direction of the arrow E. At the same time it is possible to rotate the

frame 12 in direction of the arrow C into that central plane through column 3 which is perpendicular to the plane in which the column can be lowered and raised. Due to this design the collapsed device fills a small space and is easy to store. In order to put the device in operation the column 3 is put back in the vertical position; while this is done the cross-bar 9 slides on the outer edges of the plates 2 which have the shape of circular arcs, until it drops into the notches 2a under its own weight, and thus locks column 3 in position. At the same time frame 12 is rotated back into the horizontal position shown in Fig. 1. Handling is thus very simple and does not require the use of tools or the opening of any clamps or holding devices. The arrangement of frame 12 in such a way that it can be rotated has also the advantage compared to the known arrangement with fixed stand and immovable frame, that the frame can be moved up and down while the bag is filled so that the material can settle.

As shown in Figs. 7 and 8, the frame which carries the holding clamps can also contain two angle-shaped parts. One leg 18 of these angles has a circular cross-section and carries a bar 15 for the holding clamps; the other leg 19 has a square cross-section and can be shifted in the square tubular extension of a round bar which is supported in the tubular piece 10a of the carrier 10, and can be rotated in that piece. Each extension 20 has a locking screw 21 for locking the leg 19 in various positions. Both extensions 20 are provided with one stop 22 each, which is in contact with the stop 23 of the carrier 10 when the frame is in the horizontal position. This frame which is open on one side, can be adjusted to the various sizes of the bag opening with a few motions, while the width remains always the same. Compared to the known closed frame consisting of two halves, whose lateral members can be shifted within each other, this frame has the advantage that the bag can be attached from the side instead of from underneath.

It is also possible that only one arm 19 is made for extending. The clamping of the arm does not necessarily have to be done by means of a locking screw but can also be accomplished by means which are known in other fields.

Having thus described my invention, what is claimed as new and desired to be secured by Letters Patent, is:

1. A device for keeping bags open while being filled, comprising a substantially U-shaped frame, hook-shaped bag-holding clamps carried by said frame, said frame being adaptable to accommodate various sizes of bag openings, a carrier upon

which said frame is rotatably mounted, a hollow column, said carrier rotatably and telescopically engaging said column, means for locking said carrier to said column in various vertical positions thereon, a base, said column being swingably connected with said base whereby it can be lowered and raised, means for locking said column to said base in vertical position, said frame being swingably connected to said carrier whereby to be horizontally disposed when in operative position and to lie adjacent said column when in inoperative position, said column being further provided with a pivoted footplate, a pair of guide plates, one end of said footplate being in contact with said guide plates, each of said guide plates being provided with an arc-shaped edge and a notch at a point opposite the pivot of said footplate, a rotatable holding-member attached to said column, said holding-member being provided with a locking part adapted to slide on the edges of said guide plates when said column is swiveled, and said locking part adapted to drop-in locking engagement with said notches when said column is in vertical position.

2. A device according to claim 1, including said carrier being provided with a member in shape of a bushing and stops, said bushing supporting a part of said frame so that the latter can be rotated, said frame having a rotary part, said part being provided with stops, said stops for arresting said frame in said horizontal position by making contact with said stops on said carrier, a center-piece connected to said carrier, said frame comprising two angle-shaped parts, each part comprising an extension and a leg projecting therefrom, said legs carrying said holding clamps, said extensions being connected to said center-piece and at least one of said extensions being adapted to be extended relatively to said center-piece, and means for locking said extensions in selective positions, said clamps being pivotally connected to said frame, each of said clamps having substantially arcuate free ends whereby a bag may be slid between said frame and said clamps in self-locking position.
